JAMES R. BALSLEY, OF SWISSVALE, PENNSYLVANIA, ASSIGNOR TO WESTINGHOUSE ELECTRIC & MANUFACTURING COMPANY, A CORPORATION OF PENNSYLVANIA

SIGNALING SYSTEM

Application filed April 12, 1926. Serial No. 101,287.

My invention relates to amplifying systems and it has particular reference to systems of the type generally known as super-regenerative, in which the amplification obtained is enormously greater than in the usual or simple type of regenerative system.

The super-regenerative type of system, which is disclosed by the patent to E. H. Armstrong, No. 1,424,065, granted July 25, 1922 has many advantages, but it has been found difficult to tune and maintain in a stable operating state. After it has once been tuned to receive signals from a given station, the system, as disclosed by Armstrong, gives enormous amplification, but as is well known to those skilled in the art, it is quite difficult to tune the system to a desired carrier frequency on account of the numerous noises always present when the system is in operation.

It has also been found that in order to obtain the greatest possible amplification, it is expedient to keep the variation frequency just at the edge of audibility, which causes a whistling sound difficult to filter out even though elaborate filter networks are used. It has also been noted that the amplification obtained by the super-regenerative system varies in proportion to the difference between the local variation frequency and the frequency of the incoming carrier wave and that signals of very high frequency, corresponding to a wave length of say 100 meters, are amplified more than signals on the frequencies usually used in broadcasting.

It is an object of my invention to provide a super-regenerative system which will be simple and easy to adjust and which, in the hands of even an unskilled operator, will be capable of giving extraordinarily loud signals.

Another object of my invention is to so construct a super-regenerative system that the variation frequency need not be audible.

Still another object of my invention is to provide a super-regenerative system in which the amplification will be substantially constant over a wide range of frequencies.

50 A further object of my invention is to

provide a super-regenerative system which will be stable in operation and which will require a minimum of tuning controls.

A still further object of my invention is to provide means whereby a super-regenerative system is prevented from radiating the local variation frequency, which radiation has proved objectionable in some cases.

These objects as well as others which will be more clearly brought out later, I attain by employing a detector tube between the source of varying electric currents and the super-regenerative system. A tube so located may properly be termed a "blocking" detector tube. In addition, I make use of a local oscillation generator, the output of which is passed into either the grid or plate circuit of this blocking tube.

The frequency of the oscillation generator is so chosen that the resultant frequency obtained by interaction with the incoming high frequency is much higher than such incoming frequency. This new frequency is then applied to the input circuit of a super-regenerative system, which circuit is tuned to a definite high frequency and remains fixed in tuning.

By stepping up the incoming frequency, I am enabled to employ a much higher variation frequency than is usual in the super-regenerative system, which frequency may be well above the limit of audibility. At the same time, I am enabled to maintain constantly a very large difference between the stepped-up frequency and the variation frequency of the super-regenerative system, which large difference results in extremely high amplification as is well known in the art.

As stated above, the super-regenerative system input circuit is kept tuned to a definite frequency and it has been found by experiment that a frequency of three thousand kilocycles or higher is the most expedient to use. Leaving the input circuit fixed reduces the tuning controls to be manipulated to two, namely that of the detector input circuit and that of the frequency determining circuit of the above mentioned local oscillation generator.

The frequency of the incoming signal may lie anywhere in the broadcasting range but by varying the tuning of the oscillation generator, the resultant frequency may be made equal to that for which the super-regenerative system input circuit is kept tuned.

The blocking detector tube has a dual function. It is a part of the apparatus for heterodyning the incoming signal up to the desired high frequency and at the same time acts to prevent the extremely powerful oscillations of the super-regenerative system from being radiated from the antenna.

For a more complete understanding of this invention reference is made to the following detailed description and claims taken in connection with the accompanying drawing.

The drawing is a diagrammatic view of a preferred form of my invention.

A frequency changing amplifier, indicated generally at A, is interposed between a source of varying electric currents indicated at B, and a super-regenerative system indicated at C. An antenna 1 is connected through an inductor 2 to ground. This is merely indicative of a source of varying electric currents and such antenna may obviously be replaced by a loop (not shown) or by some type of coupling to a conductor carrying high frequency currents, as my invention is not to be limited to a system adapted solely for use with the conventional antenna and ground connections. Coupled to the inductor 2 is shown an inductor 3 tuned by a condenser 4 shunted across the terminals thereof. This circuit 3, 4 is included in the input circuit of a thermionic tube 5, being connected through an inductor 6 to the grid 7 of the tube and through the "C" batteries 8 and 9 to the filament 10 of the same tube.

An oscillation generator comprises a thermionic tube 11 having in its grid circuit an inductor 12 shunted by a tuning condenser 13 and provided in its plate circuit with an inductor 14 coupled to the inductor 12 in order to maintain oscillations therein at a frequency determined by the constants of the grid circuit 12, 13. The oscillation generator 11, as well as the other thermionic tubes involved, are all supplied with filament potential from a source 21.

Seriously included in the grid of this oscillation generator is the "C" battery 9, which serves to maintain the grid 15 of the tube 11 at a suitable potential. The potential of the grid 7 is determined by the combined effect of the "C" batteries 8 and 9. In the circuit just described, it is entirely feasible to replace the grid-biasing means for the tube 5 by a grid leak and condenser (not shown), and any well known form of oscillation generator may be substituted for tube 11 and its attendant circuits. I may also employ a crystal, or other form of detector instead of tube 5, with such necessary modifications of

the circuit as will be obvious to those skilled in the art.

In the output circuit of the tube 5 is included an inductor 16 connected in series between the plate 17 and the "B" battery 18. Coupled to this inductor 16, and electrically connected therewith, is an additional inductor 19 which is associated with the grid 7 through a neutralizing condenser 20, the purpose of which will be brought out later in the description.

The apparatus indicated to the right of the dotted line and designated by the letter C is substantially the same as that shown in Fig. 12 of the Armstrong patent above referred to, and, as described in that patent, consists of a system so arranged that a single tube performs simultaneously the function of amplification, generation of the variation frequency, and detection. This super-regenerative detector comprises a tube 23, in the input circuit of which is included a circuit comprising an inductor 24, shunted by a condenser 25, a "C" battery 26 and a second inductor 27 shunted by a condenser 28.

In the output circuit of this tube 23 is included serially between the plate 29 and the filament lead 30, a tickler or feed back inductor 31, a telephone or similar device 32, another feed back inductor 33, and the "B" battery 18. A by-pass condenser 22 is connected from a point between the telephone 32 and the tickler 31 to the filament of the super-regenerative detector tube, which shunts away from the telephone the radio frequency oscillations necessarily present in the tickler coil 31 in order to secure regeneration at the frequency to which the circuit 24, 25 is tuned. The manner in which this super-regenerative detector system functions is thoroughly explained in the said patent to Armstrong and need not be described in detail.

In operation, the circuit composed of the inductor 3 and the condenser 4 is tuned to the frequency of the incoming carrier wave. The oscillation generator 11 is then tuned and the coupling between inductors 6 and 12 is so adjusted that a definite and constant high-frequency potential is impressed between the grid 7 and the filament 10 of the detector tube 11. This frequency is so chosen that the resultant of this interaction with the incoming high frequency is the frequency to which the input circuit 24, 25 of the super-regenerative system is tuned.

For example, if the incoming signal has a frequency of 500 kilocycles per second, the frequency of the oscillation generator 11 is made 3500 kilocycles per second. The difference in frequency is then 3000 kilocycles per second, which is the frequency to which the input circuit comprising inductor 24 and condenser 25 is tuned. This resultant frequency, as is well known to those skilled in the art,

carries the same modulation that is carried by the original incoming signal.

Because of the rectifying action of the tube 5, the resultant frequency appears in the output inductor 16 and by reason of the coupling existing between the inductors 16 and 24 it is impressed across the grid-filament circuit of the super-regenerator detector tube 23.

The variation frequency of the super-regenerative system is controlled by the constants 10 of the circuit composed of the inductor 27 and the condenser 28, while regeneration at the frequency to which the circuit 24, 25 is tuned is secured by the coupling between the inductor 24 and the tickler or feed-back inductor 31.

The insertion of the blocking detector tube 5 between the source of variable currents 2 and the super-regenerative system prevents, 20 to a large extent, radiation of the variation frequency. In order to make sure that the tube 5 does not oscillate and to further prevent feeding back the variation frequency, the neutralizing inductor 19 and the condenser 20 are provided. This arrangement serves to feed back to the grid a voltage in the proper phase to neutralize any feed back directly through the capacity existing between the plate 17 and the grid 7 and prevents local oscillations from being set up in 30 the circuits associated with the tube 5.

By reason of the fact that the output of the detector tube is always at a definite frequency, there is no necessity for changing the 25 tuning of the circuits of the super-regenerative system, which may accordingly be adjusted to a state of maximum efficiency and left in such adjustment. Accurate and permanent tuning may be secured by piezo-electric crystals if preferred.

Although wide variation of the dimensions 40 of the apparatus are possible, good results may be obtained over the range of frequencies now ordinarily used for broadcasting by circuits having the constants stated below. Assuming the input capacity of the tubes used as being 30 micro-microfarads, the inductor 3 is preferably made to have an inductance of 234 microhenries while the condenser 4 should have a maximum capacity of .00035 45 microfarads. The inductor 12 has an inductance of 50 microhenries, while the condenser 13 should have a maximum capacity of .00012 microfarads, the inductor 14 being sufficiently large to insure steady oscillation.

The tuning range of the oscillator will accordingly be from 4500 kilocycles to 3500 kilocycles, thus permitting the efficient heterodyning of any frequency lying in the 50 present broadcast range of 500 kilocycles to 1500 kilocycles. The inductors 16 and 19 are each preferably about one half the number of turns of the inductor 24, while the condenser 20 may have a maximum capacity 65 equal to grid-plate capacity of tube used.

The inductor 24 forming the input of the super-regenerative system is preferably given a value of 150 microhenries, while the condenser 25 has a fixed value of .00002 microfarads.

The tickler or feed back inductor 31 is made sufficiently large to assure easy oscillation. I have found that inductor 27 may be a duolateral coil of .128 henries, the shunting condenser 28 having a capacity of not less than .0015 microfarads for greatest efficiency. The inductor 33 may be a duolateral coil of .1 henries. The two inductors 27 and 33 together with condenser 28 give a variation frequency of about 20,000 cycles per second.

The super-regenerative system indicated at C may obviously be replaced by any one of the systems disclosed in the patent to Armstrong referred to previously, Fig. 12 of that patent having been chosen merely for the sake of convenience. It is also obvious that a different type of oscillation generator and accompanying circuits may be used, and it is quite feasible to amplify the incoming signal previous to its being applied to the grid-filament circuit of the detector tube 5.

One of the principal advantages secured by my invention is the ease with which the enormous amplification of the super-regenerative circuit may be secured. It is not necessary for the operator to concern himself about the adjustments of that portion of the system to the right of the dotted line in the drawing, as this section, when once adjusted, remains fixed. In order to pick up and tune in on any station within range, it is only necessary for the operator to adjust the tuning of the circuit 3, 4 and the frequency of the oscillation generator.

I have found by experiment and actual 105 demonstration that when using three tubes of the type now known as Radiotron UX199, the amplification obtainable is equivalent to that of the usual radio frequency amplifier employing six or more tubes. It will thus be seen that in addition to being simple to operate, my invention provides a system that is 110 extremely economical.

Another feature which is advantageous is 115 that only a small energy collector is necessary when operating a system according to my invention. The usual antenna or loop may be replaced by a relatively short section of wire, or the input circuit 3, 4 may be conductively connected to almost any extended metal surface which is exposed to radiant energy. This latter feature renders my system of 120 great value in connection with portable sets which are to be used in places where it is impracticable to erect the usual type of receiving antenna.

Although I have illustrated and described herein certain specific embodiments of my invention, I am fully aware that many other 125 modifications are possible, and my inven- 130

tion is not to be limited except insofar as is necessitated by prior art and as indicated by the following claims.

I claim as my invention:

- 5 1. In combination, a super-regenerative detector system having a variation frequency, means for producing from an incoming signal a frequency higher than the carrier wave of such signal, and uni-directional coupling means between the super-regenerative system and the frequency raising means.
- 10 2. In combination, a super-regenerative system adapted to oscillate at a plurality of frequencies, means for raising the frequency of an incoming signal before applying it to the super-regenerative system, and means for preventing the oscillations generated by the super-regenerative system from affecting the frequency raising means.
- 15 3. In combination, a super-regenerative system adapted to oscillate at a plurality of frequencies and having an input circuit, an energy-receptor capable of radiating said oscillations, and means interposed between said receptor and said system for raising the frequency of an incoming signal, said last-named means comprising an oscillation generator and a rectifying device having an output circuit, said output circuit being so differentially coupled to the input circuit of said super-regenerative system that oscillations developed in the said system are precluded from reaching said energy-receptor.
- 20 4. In testimony whereof, I have hereunto subscribed my name this 29th day of March, 1926.
- 25 5. In testimony whereof, I have hereunto subscribed my name this 29th day of March, 1926.
- 30 6. In testimony whereof, I have hereunto subscribed my name this 29th day of March, 1926.
- 35 7. In testimony whereof, I have hereunto subscribed my name this 29th day of March, 1926.
- 40 8. In testimony whereof, I have hereunto subscribed my name this 29th day of March, 1926.
- 45 9. In testimony whereof, I have hereunto subscribed my name this 29th day of March, 1926.
- 50 10. In testimony whereof, I have hereunto subscribed my name this 29th day of March, 1926.
- 55 11. In testimony whereof, I have hereunto subscribed my name this 29th day of March, 1926.
- 60 12. In testimony whereof, I have hereunto subscribed my name this 29th day of March, 1926.
- 65 13. In testimony whereof, I have hereunto subscribed my name this 29th day of March, 1926.

JAMES R. BALSLEY.
